ELECTROLYTIC PROCESS OF SALVAGING
URANIUM

Robert Q. Boyer and Scott B. Kilner, Berkeley, Calif., assignors to the United States of America as represented by the United States Atomic Energy Commission

Application September 14, 1944, Serial No. 554,044

7 Claims. (Cl. 204—124)

The present invention relates to improved electrolytic processes that are especially adapted for use in conjunction with the salvage of uranium from wash solutions derived from calutrons employed in the calutron method of producing uranium enriched with U^{235} .

In the copending application of Ernest O. Lawrence, Serial No. 557,784, filed October 9, 1944, which issued as U. S. Patent No. 2,709,222 on May 24, 1955, there is disclosed a "calutron," a machine designed to separate the constituent isotopes of an element and, more particularly, to increase the proportion of a selected isotope in an element containing several isotopes, in order to produce the element enriched with the selected isotope. More specifically, the calutron mentioned is especially designed to produce uranium enriched with the isotope U^{235} .

In the copending application of James M. Carter and Martin D. Kamen, Serial No. 532,159, filed April 21, 1944, which issued as Patent No. 2,758,006 on August 7, 1956, there is disclosed an improved process of producing uranium enriched with U^{235} employing the calutron method and comprising first-stage and second-stage calutrons. In accordance with this process, uranium of natural or normal isotopic composition is treated in a first-stage calutron in order to produce as a product uranium singly enriched with U^{235} , which uranium singly enriched with U^{235} is treated in a second-stage calutron in order to produce as a product uranium doubly enriched with U^{235} , which uranium doubly enriched with U^{235} may be used commercially. In the operation of either a first-stage calutron or a second-stage calutron the compound UCl_4 is treated, whereby a residue of the UCl_4 is deposited on the parts of the calutron disposed in the source region thereof, metallic uranium enriched with U^{235} is deposited in the first pocket of the collector of the calutron, and metallic uranium impoverished with respect to U^{235} is deposited in the second pocket of the collector of the calutron. The deposit of UCl_4 is recovered by a water wash step and the deposits of metallic uranium are separately recovered by acid wash steps; and the three wash solutions are separately purified, if required, to produce three separate batches of a given compound of uranium. In this process, a first batch of the uranium compound mentioned, produced from the water wash derived from a first-stage calutron, is then converted back to UCl_4 for re-treatment in the first-stage calutron, and a second batch of the uranium compound mentioned, produced from the water wash derived from a second-stage calutron, is then converted back to UCl_4 for re-treatment in the second-stage calutron.

In the copending application of Martin D. Kamen and Abel De Haan, Serial No. 542,378, filed June 27, 1944, there is disclosed an improved process of purifying a water wash solution of the character mentioned in order to separate uranium from metallic impurities in the solution. In accordance with this process, a water wash solution containing uranium, copper, nickel, iron and chromium in the form of chlorides is first concentrated; and the concentrated solution containing UO_2^{2+} , Cu^{2+} ,

2

Ni^{2+} , Fe^{3+} and Cr^{3+} ions is then reduced electrolytically, whereby the uranyl ion, UO_2^{2+} , and the ferric ion, Fe^{3+} , are respectively reduced to the uranous ion, U^{4+} , and the ferrous ion, Fe^{2+} . Thus, the reduced solution contains U^{4+} , Cu^{2+} , Ni^{2+} , Fe^{2+} and Cr^{3+} ions; and to this reduced solution there is added oxalic acid, whereby the uranium is precipitated as $U(C_2O_4)_2 \cdot 6H_2O$ away from the metal impurities in the solution. The solution is then filtered in order to separate the uranous oxalate precipitate, leaving the metal ions mentioned in the filtrate; and the given compound of uranium is converted back to UCl_4 for further treatment in the appropriate one of the calutrons, as previously explained.

In accordance with this process, the filtrate obtained after separating the uranous oxalate contains traces of uranium and fairly large amounts of nickel, iron, copper and chromium; this solution containing U^{4+} , Ni^{2+} , Fe^{2+} , Cu^{2+} and Cr^{3+} ions is then subjected to a calcium oxalate carrier salvage treatment in order to recover the traces of uranium. This salvage treatment is very important in conjunction with the filtrate obtained from the wash water solution derived from the second-stage calutron, in view of the fact that the last-mentioned filtrate constitutes an oxalate solution of relatively large volume and the uranium contained therein has been singly enriched with U^{235} due to the previous treatment thereof in the first-stage calutron. Thus, it is essential that none of the valuable, singly-enriched uranium contained in this oxalate solution be lost to the outside.

While the salvage of the uranium from the oxalate solution mentioned, by the calcium oxalate carrier treatment, is entirely satisfactory in operation, it is essentially a laboratory process not particularly well adapted to large scale commercial use.

Accordingly, it is an object of the invention to provide an improved process of salvaging the uranium from a solution of the character mentioned that may be readily carried out on a commercial scale and in an economical manner.

A further object of the invention is to provide an improved process of salvaging traces of uranium contained in a relatively large volume of solution by treatment in an electrolytic cell.

A further object of the invention is to provide an improved process of treating in an electrolytic cell a solution derived from a calutron wash solution, whereby traces of uranium contained in the treated solution are salvaged and metal impurities contained in the treated solution are separated from the salvaged uranium.

A further object of the invention is to provide an improved electrolytic process for concentration and purification of uranium which includes reduction of uranium ion in solution from a higher to a lower oxidation state without plating out of the uranium, and simultaneous destruction of an associated anion.

A further object of the invention is to provide an improved process of decomposing electrolytically a compound that is decomposable by chlorine oxidation in solution.

A further object of the invention is to provide an improved process of decomposing electrolytically an oxalate solution.

A further object of the invention is to provide an improved process of concentrating electrolytically uranium in solution.

The invention, both as to its organization and method of operation together with further objects and advantages thereof, will best be understood by reference to the following specification taken in connection with the accompanying drawings, in which Figure 1 is a fragmentary plan view of an electrolytic cell with which there may be

carried out the process of the present invention; Fig. 2 is a fragmentary longitudinal sectional view of the electrolytic cell taken along the line 2—2 in Fig. 1; Fig. 3 is a transverse sectional view of the electrolytic cell taken along the line 3—3 in Fig. 2; Fig. 4 is a transverse sectional view of the electrolytic cell taken along the line 4—4 in Fig. 2; Fig. 5 is a transverse sectional view of the electrolytic cell taken along the line 5—5 in Fig. 2; Fig. 6 is an enlarged fragmentary sectional view of one of the anode compartments in the electrolytic cell, taken along the line 6—6 in Fig. 5; Fig. 7 is an enlarged fragmentary sectional view of the lower portion of the left-hand side wall of the upper casing section of the electrolytic cell, taken along the line 7—7 in Fig. 6, and illustrating the arrangement of the gas conduit embedded therein; Fig. 8 is a reduced side elevational view, partly in section, of the housing of the electrolytic cell; and Fig. 9 is a diagrammatic illustration of a solution treatment system in which the electrolytic cell is incorporated.

Referring now more particularly to Figs. 1 to 7, inclusive, of the drawings, there is illustrated an electrolytic cell 10 that comprises a lower casing section 11 and an upper casing section 12. The lower casing section 11 is substantially rectangular in plan, including a flat bottom wall 13, upstanding side walls 14 and upstanding end walls 15, secured together in liquid-tight relation, the perimeter of the bottom wall 13 being received in interior grooves formed in the side walls 14 and in the end walls 15 adjacent the lower edges thereof. Further, the lower casing section 11 includes a rectangular outwardly extending flange 16 disposed about the upper open end thereof and rigidly secured to the adjacent outer surfaces of the side walls 14 and the end walls 15. Similarly, the upper casing section 12 is substantially rectangular in plan, including a flat bottom wall 17, upstanding side walls 18 and upstanding end walls 19, secured together in liquid-tight relation, the lower edges of the side walls 18 and the end walls 19 being received in a rectangular groove formed in the upper surface of the bottom wall 17, and disposed inwardly from the perimeter thereof. Accordingly, the bottom wall 17 of the upper casing section 12 extends outwardly from the side walls 18 and the end walls 19 in order to define in effect a rectangular outwardly extending flange 20, disposed about the lower closed end of the upper casing section 12. Preferably, the parts of the lower casing section 11 and the upper casing section 12 are formed of laminated "Bakelite," "Textolite" or other similar insulating material.

The upper casing section 12 is assembled upon the lower casing section 11, the rectangular flanges 20 and 16 being congruent. Also, a sealing gasket 21, formed of rubber or the like, is arranged between the lower surface of the bottom wall 17 and the upper edge of the side walls 14 and the end walls 15, and extending between the flanges 20 and 16. Finally, the flanges 16 and 20 are removably secured together in liquid-tight relation by a series of bolts 22, extending through aligned openings formed therein, the ends of the bolts 22 receiving nuts 23. Washers 24 and 25 surround the shanks of the bolts 22 and are respectively disposed between the heads of the bolts 22 and the upper surface of the flange 20, and between the nuts 23 and the lower surface of the flange 16. Further, a drain pipe 26 is threaded in an opening formed in the bottom wall 13 adjacent the left-hand end wall 15, which drain pipe communicates with the interior of the lower casing section 11. The end of the drain pipe 26 terminates in a petcock 27, whereby the drain pipe 26 may be selectively opened or closed.

A number of laterally extending and longitudinally spaced-apart slots 17a are provided through the bottom wall 17 within the area bounded by the side walls 18 and the end walls 19, and a corresponding plurality of upstanding laterally extending and longitudinally spaced apart pairs of partition elements 28 are carried by the

upper surface of the bottom wall 17, the individual partition elements 28 of each pair being disposed on the opposite sides of a slot 17a. More particularly, each upstanding partition element 28 is retained in place by a pair of aligned upstanding slots 18a, formed in the inner surfaces of the side walls 18, and an aligned laterally extending recess 17b, formed in the upper surface of the bottom wall 17 adjacent a slot 17a. Thus, each partition element 28 is retained in place in upstanding position by a substantially U-shaped composite groove comprising a pair of upstanding slots 18a formed in the inner surfaces of the side walls 18 and a cooperating laterally extending recess 17b formed in the upper surface of the bottom wall 17. Finally, an upstanding laterally extending partition element 29 is carried by the upper surface of the bottom wall 17, the partition element 29 being spaced longitudinally and to the right-hand side of the partition element 28 disposed most remote from the left-hand end wall 19. Also, the upstanding partition element 29 is retained in place by a pair of upstanding cooperating slots formed in the inner surfaces of the side walls 18 and an aligned laterally extending recess formed in the upper surface of the bottom wall 17, in a manner identical to that previously explained in conjunction with each partition element 28.

The various partition elements 28 and the partition element 29 comprise rectangular plates formed of a porous semipermeable insulating material of the ceramic type, such as Alundum or sintered Pyrex glass. Collectively, the pairs of partition elements 28 and the partition element 29 constitute partition structure defining a plurality of interposed anode and cathode compartments 30 and 31, respectively, in the upper casing section 12. More particularly, the two partition elements 28 of each pair cooperate with each other and with the portions of the side walls 18 disposed therebetween to define a cathode compartment 31 having an open lower end formed by a cooperating slot 17a. Similarly, each left-hand partition element 28 of a pair cooperates with the right-hand partition element 28 of an adjacent pair and with the portions of the side walls 18 and the bottom wall 17 disposed therebetween to define an anode compartment 30 having a closed lower end. Further, the left-hand partition element 28 of the pair disposed adjacent the left-hand end wall 19 cooperates therewith and with the portions of the side walls 18 and the bottom wall 17 disposed therebetween to define the anode compartment 30 disposed immediately adjacent the left-hand end wall 19. Finally, the right-hand partition element 28 of the pair disposed adjacent the partition element 29 cooperates therewith and with the portions of the side walls 18 and the bottom wall 17 disposed therebetween to define the anode compartment 30 disposed most remote from the left-hand end wall 19.

The upper edges of the various pairs of partition elements 28 and the partition element 29 are disposed substantially flush with the upper edges of the side walls 18, and the upper edges of the side walls 18 are substantially flush with the upper edges of the end walls 19; whereby the upper edge of the upper casing section 12 is substantially flat and parallel to the bottom wall 13 of the lower casing section 11. Further, a pair of conductors in the form of bus bars 32 formed of copper or the like, are secured to the upper edges of the sidewalls 18 by a number of screws 33. The left-hand ends of the busbars 32 are secured together by a conducting strap 34 by screws 35; and a conducting terminal 36 is secured to the mid-portion of the strap 34 by a screw 37. A plurality of anode elements 38 is carried by the busbars 32 and arranged in the respective anode compartments 30. Each of the anode elements 38 comprises a substantially rectangular plate provided at its upper end with laterally and oppositely extending lugs 38a which overhang the respective busbars 32. The anode elements 38 are formed of a conducting material resistant to chlorine.

and hydrochloric acid solutions, such as graphite or platinum or a platinum-iridium alloy, and are electrically connected to the busbars 32 by terminal structure including screws 39 and flexible conductors 40. More particularly, the flexible conductors 40 are of the braid or pigtail type, one end of each pigtail 40 being brazed or soldered to the adjacent busbar 32, and the other end of the pigtail 40 being provided with an eyelet through which the associated screw 39 extends, the screw 39 extending through the adjacent lug 38a formed on the cooperating anode element 38. Thus, the terminal 36 is connected by low resistance paths to each of the anode elements 38 in multiple, whereby collectively the anode elements 38 constitute an anode.

A longitudinally extending shaft 41 is rotatably mounted in two bearing brackets 42 and 43, secured to the lower surface of the bottom wall 17 by screws 44 and 45, respectively. The bearing brackets 42 and 43 are aligned substantially along the longitudinal center-line of the bottom wall 17 and consequently of the electrolytic cell 10, the bearing bracket 42 being disposed adjacent the left-hand end wall 15, and the bearing bracket 43 being disposed remote from the left-hand end wall 15 and spaced some distance from the right-hand end wall 15. The bearing brackets 42 and 43 may suitably comprise complementary sections formed of stainless steel and secured together and to the bottom wall 17 by the screws 44 and 45, as previously noted. The shaft 41 carries a plurality of longitudinally spaced apart cathode members 46 in the form of disks. Each of the cathode members 46 is rigidly secured to the shaft 41, so that it is rotatable therewith, and extends downwardly into the lower casing section 11 and upwardly through a cooperating one of the slots 17a into a cooperating one of the cathode compartments 31 formed in the partition structure within the upper casing section 12. The cathode members 46 are formed of a conducting material resistant to chlorine and hydrochloric acid solutions that readily amalgamates with mercury, such for example, as nickel. The cathode members 46 are electrically connected to the shaft 41 in multiple and collectively constitute a cathode.

A laterally extending opening 17c is provided through the bottom wall 17 adjacent the right-hand end wall 19; and a bevel gear 47 is rigidly secured to the right-hand end of the shaft 41, whereby the upper portion of the bevel gear 47 extends upwardly through the opening 17c into the upper casing section 12, and the lower portion of the bevel gear 47 extends downwardly into the lower casing section 11. More particularly, the bevel gear 47 is provided with a collar 48 which is secured to the right-hand end of the shaft 41 by a setscrew 49 and carries a flange 50 engaging the right-hand side of the bearing bracket 43 to provide a thrust bearing for the shaft 41.

The bevel gear 47 meshes with a bevel gear 51 rigidly secured to an upstanding operating shaft 52 adjacent the lower end thereof. The extreme lower end of the operating shaft 52 is supported in a thrust bearing 53 carried by a bearing bracket 54; and the upper end of the operating shaft 52 is supported by a guide bearing 55 carried by a bearing strap 56. More particularly, the bearing bracket 54 comprises two laterally upwardly and outwardly extending legs 57, which are secured by screws 58 to the lower surface of the bottom wall 17, and a longitudinally upwardly and outwardly extending leg 59, which is secured by the screw 45 to the bearing bracket 43. The thrust bearing 53 comprises a threaded step 60 accommodating adjustment of the operating shaft 52 in the vertical direction, and consequently proper mesh between the bevel gear 51 carried thereby and the bevel gear 47 carried by the shaft 41. The bearing strap 56 extends laterally across the upper casing section 11, and the opposite ends thereof are suitably anchored to the upper edges of the side walls 18 by screws 61.

A pool of mercury 62 is arranged in the lower casing

section 11, the volume of the mercury constituting the pool being such that columns of mercury rise in the slots 17a into the cathode compartments 31. Preferably, the columns of mercury rise into the cathode compartments 31 a slight distance above the upper surface of the bottom wall 17, whereby the shaft 41 and the lower segments of the cathode members 46 are immersed in the mercury pool 62. An upstanding cathode plate 63 extends through the upper casing section 12 downwardly through the opening 17c and terminates in the lower casing section 11, whereby the lower end of the cathode plate 63 is immersed in the mercury pool 62. A substantially U-shaped clip 64 is rigidly secured to the cathode plate 63 and is adapted to overhang the adjacent upper edge of the right-hand end wall 19, thereby securely to retain the cathode plate 63 in position.

Further, a body of electrolyte 65 is arranged in the upper casing section 12 as a head upon the mercury pool 62, the body of electrolyte 65 filling the varicus anode and cathode compartments 30 and 31, respectively, and electrically communicating through the porous partition structure including the partition elements 28 and 29, the mass of the body of electrolyte 65 being such that the upper segments of the cathode members 46 are completely immersed therein. The anode compartments 30 in the upper casing section 12 are arranged in groups, each group containing several adjacent individual anode compartments, the individual anode compartments in each group being connected in series relation, and the different groups of anode compartments being connected in parallel relation by a first conduit system. Similarly, the cathode compartments 31 in the upper casing section 12 are arranged in groups, each group containing several adjacent individual cathode compartments, the individual cathode compartments in each group being connected in series relation, and the different groups of cathode compartments being connected in parallel relation by a second conduit system.

Considering now the electrolytic cell 10 in greater detail, the partition structure comprises nine pairs of partition elements 28, whereby nine individual cathode compartments 31 are formed in the upper casing section 12 and arranged in longitudinally spaced apart relation, each of the cathode compartments 31 communicating through the associated slot 17a with the lower casing section 11. Also, the rotatably mounted shaft 41 carries nine longitudinally spaced apart cathode members 46 which extend through the respective slots 17a into the respective cathode compartments 31. Further, the partition structure comprising the nine pairs of partition elements 28 and the partition element 29 forms ten individual anode compartments 30 in the upper casing section 12, arranged in longitudinally spaced apart relation and in interposed relation with respect to the cathode compartments 31. Thus, in the partition structure an anode compartment 30 is positioned on either side of each cathode compartment 31. The ten anode compartments 30 are arranged in three groups, two end groups of three individual anode compartments each and a middle group of four individual anode compartments. The three groups of anode compartments 30 are connected in parallel, and the individual anode compartments 30 in each group are connected in series relation by the first conduit system mentioned. Similarly, the nine cathode compartments 31 are arranged in three groups of three individual cathode compartments each. The three groups of cathode compartments 31 are connected in parallel and the individual cathode compartments 31 in each group are connected in series relation by the second conduit system mentioned.

Referring now more particularly to Figs. 1, 2 and 9, the first conduit system mentioned comprises three inlet pipes 101, respectively serving the three groups of anode compartments 30 and respectively communicating with the first, fourth and eighth individual anode compartments.

ments 30 positioned from the right-hand side of the electrolytic cell 10 toward the left-hand side thereof, as viewed in the figures mentioned. Also, the first conduit system mentioned comprises three outlet pipes 102, respectively serving the three groups of anode compartments 30 and respectively communicating with the third, seventh and tenth individual anode compartments 30. The adjacent ends of the individual anode compartments in each group are connected in series relation between the associated inlet pipe 101 and the associated outlet pipe 102 by U-shaped header pipes 103. In conjunction with the first conduit system, it is noted that a series of aligned openings 18b are formed in the side walls 18 and communicate with the anode compartments 30 in order to receive the various pipes 101, 102 and 103, the openings 18b being disposed well above the lower ends of the anode elements 38 so that the lower portions of the anode elements are completely immersed in the body of electrolyte 65.

Accordingly, it will be understood that a first stream of electrolyte may be conducted from a first of the inlet pipes 101 through a first group of three individual anode compartments 30 in series relation to a first of the outlet pipes 102. Similarly, a second stream of electrolyte may be conducted from a second of the inlet pipes 101 through the second group of four individual anode compartments 30 in series relation to a second of the outlet pipes 102. Finally, a third stream of electrolyte may be conducted from a third of the inlet pipes 101 through the third group of three individual anode compartments 30 in series relation to a third of the outlet pipes 102. Accordingly, the first conduit system connects the individual anode compartments 30 in the electrolytic cell 10 in parallel series relation.

The second conduit system mentioned comprises three inlet pipes 104 respectively serving the three groups of cathode compartments 31 and respectively communicating with the first, fourth and seventh individual cathode compartments 31 positioned from the right-hand side of the electrolytic cell 10 toward the left-hand side thereof, as viewed in the figures mentioned. Also, the second conduit system mentioned comprises three outlet pipes 105 respectively serving the three groups of cathode compartments 31 and respectively communicating with the third, sixth and ninth individual cathode compartments 31. The adjacent ends of the individual cathode compartment in each group are connected in series relation between the associated inlet pipe 104 and the associated outlet pipe 105 by U-shaped header pipe 106. In conjunction with the second conduit system, it is noted that a series of aligned openings 18c are formed in the side walls 18 and communicate with the cathode compartments 31 in order to receive the various pipes 104, 105 and 106, the openings 18c being disposed above the cathode members 46 so that the upper segments of the cathode members are completely immersed in the body of electrolyte 65.

Accordingly, it will be understood that a first stream of electrolyte may be conducted from a first of the inlet pipes 104 through a first group of three individual cathode compartments 31 in series relation to a first of the outlet pipes 105. Similarly, a second stream of electrolyte may be conducted from a second of the inlet pipes 104 through the second group of three individual cathode compartments 31 in series relation to a second of the outlet pipes 105. Finally, a third stream of electrolyte may be conducted from a third of the inlet pipes 104 through the third group of three individual cathode compartments 31 in series relation to a third of the outlet pipes 105. Accordingly, the second conduit system connects the individual cathode compartments 31 in the electrolytic cell 10 in parallel series relation.

Again referring to Figs. 1 to 7, inclusive, it is noted that two longitudinally extending pipes 110 and 111 are respectively embedded in the two side walls 18 of the

upper casing section 12, the pipes 110 and 111 being respectively embedded in the left-hand and right-hand side walls 18, as viewed in Figs. 5 and 6. More particularly, the pipe 110 is arranged in a longitudinally extending opening formed in the left-hand side wall 18 adjacent the lower edge thereof and cemented in place in a fluid-tight manner by a layer of a suitable cement 112; and the pipe 111 is arranged in a longitudinally extending opening formed in the right-hand side wall 18 adjacent the lower edge thereof and cemented in place in a fluid-tight manner by a layer of a suitable cement 113. The cement employed in the layers 112 and 113 may be of any suitable type, such, for example, as "Bakelite."

A series of longitudinally spaced apart openings 110a are formed in the pipe 110 and communicate through connecting and registering downwardly extending holes 114 provided in the layer of cement 112 and in the left-hand side wall 18, the holes 114 communicating with the various anode compartments 30. More particularly, each hole 114 formed in the left-hand side wall 18 communicates with the associated anode compartment 30 adjacent the lower left-hand corner thereof and on the front side of the anode element 38 arranged in the anode compartment 30, as viewed in Fig. 6. Similarly, a series 20 of longitudinally spaced apart openings 111a are formed in the pipe 111 and communicate through connecting and registering downwardly extending holes 115 provided in the layer of cement 113 and in the right-hand side wall 18, the holes 115 communicating with the various anode compartments 30. More particularly, each hole 115 formed in the right-hand side wall 18 communicates with the associated anode compartment 30 adjacent the lower right-hand corner thereof and on the back side of the anode element 38 arranged in the anode compartment 30, as viewed in Fig. 6. Accordingly, the pipe 110 communicates through the openings 110a with the lower left-hand corners of the various anode compartments 30 on the front sides of the anode elements 38; while the pipe 111 communicates through the openings 111a with the lower right-hand corners of the various anode compartments 30 on the back sides of the anode elements 38.

The pipes 110 and 111 form a part of a third conduit system containing gas under pressure, whereby the gas may be forced through the pipes 110 and 111 and the 45 respectively communicating holes 114 and 115 into the various anode compartments 30 on either side of the anode elements 38. Also, inlet and outlet conduits 116 and 117 are supported in openings formed in the end walls 15 of the lower casing section 11 and form a 50 part of a fourth conduit system, whereby mercury may be circulated through the mercury pool 62 contained in the lower casing section 11.

Referring now to Fig. 8, the electrolytic cell 10 is arranged in a substantially fluid-tight housing 120 comprising lower and upper housing sections 121 and 122, respectively, provided with outwardly directed flanges 123 and 124 secured together by a series of bolts 125 extending through aligned openings formed therein, a suitable sealing gasket 126, formed of rubber or the like, being arranged between the flanges 123 and 124. The wall of the lower housing section 121 supports two insulating bushings 127 and 128, arranged in gas-tight relation therewith, through which conductors are adapted to extend, whereby the positive and negative terminals of a 60 suitable source of supply may be respectively connected to the terminal 36 and the plate 63, shown in Figs. 1 and 2, in an appropriate manner. Also, the wall of the lower housing section 121 supports two conduits 129 and 130, arranged in gastight relation therewith, which are 65 appropriately connected to the pipes 101 and 102 and form a part of the first conduit system previously mentioned, whereby an electrolyte may be circulated through the anode compartments 30 in parallel series relation in the manner previously explained. Similarly, the wall of the lower housing section 121 supports two conduits 131 70

and 132, arranged in gastight relation therewith, which are appropriately connected to the pipes 104 and 105 and form a part of the second conduit system previously mentioned, whereby an electrolyte may be circulated through the cathode compartments 31 in parallel series relation in the manner previously explained.

Further, the wall of the lower housing section 121 supports a conduit 133, arranged in gastight relation therewith, which is appropriately connected to the pipes 110 and 111 and forms a part of the third conduit system previously mentioned, whereby gas under pressure may be conducted into the anode compartments 30 in the manner previously explained. The wall of the upper housing section 122 supports a conduit 134, arranged in gastight relation therewith, and communicating with the interior of the housing 120, whereby gas liberated from the electrolytic cell 10 and accumulated within the housing 120 may be conducted to the exterior in a manner more fully explained hereinafter. Finally, the wall of the lower housing section 121 supports two conduits 135 and 136, arranged in gastight relation therewith, which are appropriately connected to the pipes 116 and 117 and form a part of the fourth conduit system previously mentioned, whereby mercury may be circulated through the pool of mercury 62 arranged in the lower casing section 11 of the electrolytic cell 10 in the manner previously explained.

The operating shaft 52 extending into the electrolytic cell 10 is suitably connected to an electric motor 137 supported by a bracket 138 carried by the wall of the lower housing section 121; and the wall of the lower housing section 121 supports an insulating bushing 139, arranged in gastight relation therewith, through which conductors are adapted to extend in order to supply the electric motor 137 with an operating current.

Considering now the general operation of the electrolytic cell 10, when the operating circuit for the electric motor 137 is completed, operation thereof is initiated, whereby the operating shaft 52 is rotated, causing the bevel gear 51 to drive the bevel gear 47 in order to rotate the shaft 41. As the shaft 41 is rotated the cathode members 46 are rotated, whereby repeatedly the lower segment of each of the cathode members or disks 46 is removed from the mercury tool 62 and immersed in the body of electrolyte 65 in the associated one of the cathode compartments 31, and the upper segment thereof is removed from the body of electrolyte 65 in the associated one of the cathode compartments 31 and immersed in the mercury pool 62. The electric motor 137 is operated at a suitable speed in view of the gear reduction ratio between the bevel gears 51 and 47 so that the shaft 41 and consequently the disk 46 rotate at the required speed, as explained more fully hereinafter. Also, the operating circuit for the electrolytic cell 10 is completed, the anode terminal 36 and the cathode plate 63 being respectively connected to the positive and negative terminals of the source of direct current supply, whereby the body of electrolyte 65 floating on the pool of mercury 62 is electrolyzed. More particularly, a first solution to be treated in the electrolytic cell 10 is conducted through the anode compartments 30 via the first conduit system mentioned; and a second solution to be treated in the electrolytic cell 10 is conducted through the cathode compartments 31 via the second conduit system mentioned; the two solutions forming an electrolyte system comprising the body of electrolyte 65, as explained more fully hereinafter. Also, gas under pressure is conducted into the anode compartments 30 via the third conduit system mentioned for a purpose more fully explained hereinafter. Finally, mercury is conducted through the lower casing section 11 via the fourth conduit system mentioned. The mercury forms a part of the pool of mercury 62, for a purpose more fully explained hereinafter.

Considering now the construction and arrangement of the component elements of the electrolytic cell 10 in greater detail, it is noted that in the specific embodiment of the electrolytic cell illustrated, each of the disks 46 has a diameter approximately 12 cm., and approximately 40% and 60% of its area are respectively immersed in the body of electrolyte 65 and in the mercury pool 62. Thus, about 80 cm.² of the area of each of the disks 46 is immersed in the body of electrolyte 65, whereby the total area of the cathode immersed in the body of electrolyte 65 is approximately 720 cm.². Employing an electrolyte constituting a hydrochloric acid solution, an electrolytic current within the range 150 to 175 amperes has been obtained, whereby the electrolytic current was approximately 0.2 ampere per cm.² of area of the cathode, which value is well within the usual operating limits, 0.1 to 0.3 ampere per cm.² at the cathode, for electrolytic cells. The electrolytic current mentioned was obtained when several volts, e. g., about four, direct current was applied between the anode terminal 36 and the cathode plate 63. Under the operating conditions mentioned, it was found that three streams of the first solution treated, of relatively large volume, conducted through the three groups of anode compartments 30, and three streams of the second solution treated, of relatively small volume, conducted through the three groups of cathode compartments 31, permitted operation without undue heating of either the electrolytic cell 10 or the two solutions. More particularly, each of the three streams of the first solution comprised a flow of approximately 50 cc. per minute, while each of the three streams of the second solution comprised a flow of approximately 5 cc. per minute, the temperature rise of the two solutions being of the order of 55° C. Specifically, 150 cc. of the first solution per minute and 15 cc. of the second solution per minute were conducted through the electrolytic cell 10, experiencing a temperature rise from 15°-20° C. to 70°-75° C. When the two solutions were conducted through the electrolytic cell 10 at the rate and under the operating conditions mentioned, there was no undue heating of the component parts of the electrolytic cell. It will be understood that these particular flow rates, as well as the ratios between them, are given merely for the purpose of better illustrating the invention, and that wide variations may be made therein without sacrificing any of the advantages of the invention. In general, it is preferred to maintain such relative rates of flow of the respective electrolyte solutions as will give satisfactory transfer of uranium from the first solution to the second, without at the same time causing undue heating of the cell. It is also preferred to maintain the flow conditions such that the respective electrolytes in the anode and cathode compartments are at substantially the same level, in order to prevent mechanical transfer of electrolyte through the partitions.

Now considering the operation of the electrolytic cell 10, in conjunction with the detailed treatment of the two solutions in accordance with the present process, reference is again made to Fig. 9. The anode and cathode compartments 30 and 31 are initially filled with a body of electrolyte comprising about 3 N hydrochloric acid; then operation of the electrolytic cell 10 is initiated in the manner previously explained. More particularly, the flow of the first solution to be treated through the anode compartments 30 via the first conduit system mentioned is adjusted to approximately 150 cc. per minute, this first solution constituting the filtrate obtained after separating the uranous oxalate precipitate following the precipitation step in the process disclosed in the previously mentioned application of Kamen and De Haan. More specifically, the first solution is an oxalic acid solution, about 1 N to 3 N in hydrogen ion, and normally contains traces of uranium and fairly large amounts of nickel, iron, copper and chromium, as previously noted. Ordinarily, the first solution, or oxalate solution, contains the materials men-

tioned in the ionic forms U^{++++} , Ni^{++} , Fe^{++} , Cu^{++} and Cr^{++} , although some of the uranium and the iron might possibly be in the ionic forms UO_2^{++} and Fe^{+++} ; and the general case will be considered, wherein the first solution is assumed to contain the following ions: UO_2^{++} , U^{++++} , Ni^{++} , Fe^{++} , Cu^{++} and Cr^{++} .

The flow of the second solution to be treated through the cathode compartments 31 via the second conduit system mentioned is adjusted to approximately 15 cc. per minute, this second solution constituting ordinary hydrochloric acid, about 12 N. Also, the flow of the gas through the anode compartments 30 via the third conduit system mentioned is suitably adjusted, whereby the gas is bubbled and thoroughly dispersed through the electrolyte contained in the anode compartments 30, this gas being introduced adjacent the lower corners of the anode compartments well below the surface of the electrolyte contained therein. This gas comprises a mixture of nitrogen and chlorine, nitrogen being employed as a carrier for the chlorine and the chlorine being employed as an oxidizing agent, for a purpose more fully explained hereinafter. Further, the flow of mercury through the lower casing section 11 via the fourth conduit system mentioned is suitably adjusted, whereby pure mercury is introduced into the mercury pool 62 and contaminated mercury is withdrawn therefrom, as explained more fully herein-after.

Shortly after operation of the electrolytic cell is initiated, the first and second solutions respectively displace the initial body of electrolyte 65 in the anode and cathode compartments 30 and 31, and the mixture of nitrogen and chlorine is bubbled through the first solution conducted through the anode compartments 30, whereby the oxalate solution is decomposed in order to prevent possible precipitation of minor amounts of uranous oxalate in the anode compartments. More particularly, the oxalate solution is readily decomposed by virtue of two independent, although cumulative, chemical actions which take place in the anode compartments. In the first place, the oxalate solution is decomposed into carbon dioxide by anodic oxidation, due to contact between the oxalate ions and the anode elements 38 in the anode compartments 30, as indicated below:

In the second place, the oxalate solution is decomposed into carbon dioxide and hydrochloric acid by chlorine oxidation, due to contact between the oxalate solution and the chlorine bubbled therethrough in the anode compartments 30, as indicated below:

It is noted that the decomposition of the oxalate solution by chlorine oxidation is enhanced by virtue of the increased temperature of the oxalate solution as a result of the treatment in the electrolytic cell 10. The carbon dioxide thus produced in the anode compartments 30 escapes therefrom, along with some of the chlorine and virtually all of the nitrogen originally introduced into the oxalate solution therein.

Furthermore, the hydrochloric acid thus produced in the anode compartments 30 by chlorine oxidation, as well as the hydrochloric acid conducted through the cathode compartments 31, is decomposed to a considerable extent by the electrolytic current into hydrogen and chlorine. The hydrogen ion migrates toward the cathode members 46, where hydrogen is liberated to some extent, and then escapes from the cathode compartments 31, while the chloride ion migrates to the anode elements 38, where chlorine is liberated freely, and then escapes from the anode compartments 30. These gases (hydrogen, nitrogen, chlorine and carbon dioxide) escape from the anode and cathode compartments 30 and 31 in the electrolytic cell 10, accumulate within the interior of the surrounding housing 120, and are conducted therefrom by

way of the conduit 134 carried by the upper housing section 122. Preferably, the gases mentioned are suitably pumped from the interior of the housing 120, although this is not entirely necessary in view of the fact that the amounts of nitrogen and chlorine are adequate to build up a slight pressure within the housing 120.

Also, it is noted that while it is preferable that a mixture of nitrogen and chlorine be introduced into the anode compartments 30 via the third conduit system in order to obtain rapid decomposition of the oxalate solution, this step is not essential as the oxalate solution may be decomposed quite satisfactorily entirely by anodic oxidation. Of course, it will be understood that when the oxalate solution is decomposed entirely by anodic oxidation, the rate of decomposition is correspondingly decreased. Furthermore, aside from the fact that the introduction of the mixture of nitrogen and chlorine into the anode compartments 30 is productive of decomposition of the oxalate solution by chlorine oxidation, it has been found to be desirable also from the standpoint that the bubbling of the gas through the first solution conducted through the anode compartments 30 produces a stirring or agitating effect, resulting in an increased contact between the oxalate solution and the anode elements 38 in the anode compartments 30 and the consequent increased rate of decomposition of the oxalate solution due to anodic oxidation, as previously explained. Further, it is pointed out that the above-mentioned stirring or agitation of the oxalate solution in the anode compartments 30 may be brought about entirely by the introduction of only nitrogen via the third conduit system. Also, instead of introducing a mixture of nitrogen and chlorine via the third conduit system, chlorine alone may be introduced into the anode compartments 30 in order to obtain the decomposition of the oxalate solution by chlorine oxidation in the manner explained. Finally in this connection, it appears that the chlorine produced as a result of the decomposition of the second solution conducted through the cathode compartments 31, which migrates to the anode elements 38 in the anode compartments 30, also accounts for some of the decomposition by chlorine oxidation of the oxalate solution in the anode compartments, regardless of whether gas is introduced via the third conduit system into the anode compartments in the manner explained.

Also, as the first solution is conducted through the anode compartments 30 of the electrolytic cell, it is subjected to electrolysis as previously explained, whereby the contained ions are diffused by the electrolytic current through the partition elements 28 into the second solution conducted through the cathode compartments 31. The flow of the first solution through the anode compartments 30 of the electrolytic cell 10 is appropriately correlated with respect to the electrolytic current therethrough, so that substantially all of the uranium and other metal ions are transferred by electrolytic diffusion from the first solution to the second solution, the first solution leaving the electrolytic cell 10 containing only minor traces of uranium, nickel, iron, copper and chromium in the original ionic forms: UO_2^{++} , U^{++++} , Ni^{++} , Fe^{++} , Fe^{+++} , Cu^{++} and Cr^{++} . In view of the fact that substantially all of the uranium and other metal ions are transferred from the first solution to the second solution, a considerable concentration of the uranium in solution is effected, as the rate of flow of the second solution is only approximately one-tenth of that of the first solution, as previously explained.

Furthermore, substantially all of the metal ions except uranium transferred to the second solution are reduced by the electrolytic current to the metallic state; while the uranium ions transferred to the second solution are reduced by the electrolytic current to the ionic form, U^{++++} , in the event they are not already in this form, substantially none of the uranium ions being reduced to the metallic state, U^0 , due to the fact that uranium in-

herently possesses a high over-voltage. More particularly, the Fe^{+++} ion is first reduced to the Fe^{++} ion and then to the metal state Fe^0 , while the Ni^{++} , Cr^{++} and Cu^{++} ions are respectively reduced to the metal states Ni^0 , Cr^0 and Cu^0 , which metal impurities in the second solution in the cathode compartments 31 are carried by the rotating disks 46 into the mercury pool 62. The metal impurities carried into the mercury pool 62 by the rotating disks 46 are either trapped therein or amalgamated therewith, whereby the second solution conducted through the cathode compartments 31 is kept substantially free of metal impurities liberated therein incident to the electrolysis. Specifically, the copper, chromium and nickel impurities readily amalgamate with the mercury in the mercury pool 62, whereas the iron impurity is trapped therein. In view of the fact that pure mercury is continuously conducted through the lower casing section 11 of the electrolytic cell 10, the metal impurities introduced into the mercury pool 62 are conducted therefrom along with the mercury.

Of course, it will be understood that the mercury conducted from the lower casing section 11 of the electrolytic cell 10 is subsequently purified and again conducted thereto, in order to prevent undue contamination of the mercury in the mercury pool 62 and to effect the transfer of the metal impurities mentioned therefrom. Accordingly, the second solution conducted from the electrolytic cell 10 comprises a hydrochloric acid solution containing substantially all of the uranium, in the ionic form U^{++++} , and virtually none of the nickel, iron, chromium and copper impurities. Thus, the treatment of the two solutions in the electrolytic cell is effective to transfer substantially all of the uranium contained in the relatively large volume of the first solution to the relatively small volume of the second solution, and to remove virtually all of the metal impurities from the first solution without introducing substantially any of these metal impurities into the second solution, the metal impurities being removed from the first solution by electrolysis and introduced into the mercury which is circulated through the lower casing section of the electrolytic cell.

The first solution, after it is conducted from the electrolytic cell, may be discarded or subjected to further salvage treatment in order to recover any minor traces of the contained uranium; the second solution, after it is conducted from the electrolytic cell, is then subjected to further salvage treatment in order to recover the contained uranium; while the impurities recovered from the mercury circulated through the lower casing section of the electrolytic cell may be salvaged in order to recover any minor traces of uranium that may be trapped therein.

It will be understood that although the present invention is particularly useful for the separation and concentration of uranium from impure uranium oxalate solution, it also contemplates electrolytic processes wherein other solutions, and/or other operational conditions such as rates of flow, current densities, etc., are employed. Solutions of metal salts other than uranium salts may be passed in non-mixing ion-transfer relation with other acidic electrolytes to separate and concentrate the metals. Substantially any compound that is decomposable by chlorine oxidation may be decomposed or oxidized by electrolysis in a system comprising a solution containing chloride ion in ion transfer relation with a solution of the compound. Other known oxidizing gases than chlorine may be bubbled through the solution to assist in oxidation. Thus, it will be clear that the process of the present invention is not restricted to the illustrative details given.

In view of the foregoing, it is apparent that there has been provided an improved process of salvaging the uranium from a solution of the character and composition mentioned, derived from calutrons employed in the calutron method of producing uranium enriched with U^{235} .

While there has been described what is at present con-

sidered to be the preferred embodiment of the invention, it will be understood that various modifications may be made therein and it is intended to cover in the appended claims all such modifications as fall within the true spirit and scope of the invention.

What is claimed is:

1. The process of concentrating uranium in solution by treatment in an electrolytic cell including anode and cathode compartments comprising passing at a relatively high rate of flow a first solution containing uranium and oxalate ions through the anode compartment of the electrolytic cell, passing at a relatively low rate of flow an acidic second solution through the cathode compartment of the electrolytic cell in ion transfer and non-intermixing relation with said first solution, and simultaneously subjecting the two solutions to electrolysis in the electrolytic cell to transfer said uranium ions from said first solution to said second solution and concentrate said uranium ions therein.
2. The process of concentrating uranium in solution by treatment in an electrolytic cell including anode and cathode compartments separated by a porous diaphragm comprising passing at a relatively high rate of flow a first solution containing uranium and oxalate ions through the anode compartment of the electrolytic cell, passing at a relatively low rate of flow an acidic second solution through the cathode compartment of the electrolytic cell, and simultaneously subjecting the two solutions to electrolysis in the electrolytic cell to transfer said uranium ions from said first solution to said second solution and to concentrate said uranium ions therein.
3. The process of concentrating uranium in solution by treatment in an electrolytic cell including anode and cathode compartments separated by a porous diaphragm comprising passing at a relatively high rate of flow an oxalate solution containing uranium ions through the anode compartment of the electrolytic cell, passing at a relatively low rate of flow a hydrochloric acid solution through the cathode compartment of the electrolytic cell, and simultaneously subjecting the two solutions to electrolysis in the electrolytic cell to transfer said uranium ions from said oxalate solution to said hydrochloric acid solution wherein said uranium ions are concentrated.
4. The process of forming a concentrated solution of uranium which comprises passing a hydrochloric acid solution of about 12 N concentration at a relatively low volume per unit time in contact with mercury and in substantially non-mixing, ion-transfer relation with an oxalate solution containing uranium in small concentration along with ions of the metals selected from the group consisting of iron, copper, nickel, and chromium and flowing at a relatively large volume per unit time, electrolyzing said solutions to cause a transfer of chloride ions from said acid solution to said oxalate solution and of the uranium and other metal ions from said oxalate solution to said hydrochloric acid solution and to effect a deposition of metal other than uranium on and in the mercury and oxidation of oxalate ions and of the chloride ions to form chlorine gas, and recycling said chlorine gas to contact said oxalate solution.
5. The process of fractionating an oxalate solution containing uranium and other metal ions including those of iron, nickel, copper, and chromium comprising introducing said solution into the anode compartment of an electrolytic cell including anode and cathode compartments arranged in ion-transfer, nonintermixing relation to each other and having a mercury cathode, introducing an acidic solution into the cathode compartment of said cell, subjecting said solution to electrolysis to transfer said uranium and metal ions from said oxalate solution to said acidic solution to reduce said iron, nickel, copper, and chromium ions to the metallic state and to deposit the same in said mercury cathode.
6. The process of forming a purified and concentrated solution of uranium comprising passing a hydrochloric

acid solution in contact with mercury and in substantially nonintermixing ion transfer relation with a second acidic solution containing uranium and other metal ions and flowing at a higher volumetric rate, and simultaneously applying a voltage differential between said mercury and said second solution to transfer said uranium and metal ions to said second solution and to deposit said metal ions in metallic form in said mercury.

7. The process of separating uranium from other ions and forming a concentrated solution thereof, comprising passing a hydrochloric acid solution of about 12 normal concentration in contact with mercury and in substantially nonintermixing ion transfer relation with an oxalate solution of about 1 to 3 N acidity containing uranium, iron, nickel, copper, and chromium ions and flowing at a higher volumetric rate, and simultaneously transferring said uranium and other said ions by electrolysis to said hydrochloric acid solution and electrolytically depositing said other ions from said hydrochloric acid solution into said mercury.
